UNITED STATES PATENT OFFICE.

WILLIAM POTTER, OF NEW YORK, N. Y.

PLANE.

Application filed July 6, 1927. Serial No. 203,705.

This invention relates to planes and particularly to devices of this class of the dado type; and the object of the invention is to provide a plane of the class specified consisting of main and supplemental stock or body portions, the supplemental body portion being movable laterally with reference to the main body portion as well as vertically with reference thereto whereby the lower or bearing face of the supplemental body may be arranged in common alinement with or extended below the corresponding bearing face of the main body; a further object being to provide the bearing faces of the main and supplemental body portions of the plane with spaced recesses forming a plurality of spaced bearing members, and the bearing members of one body portion being adapted to interlock with the bearing members of the other body portion to form in one use of the tool, a single bearing face of the same width throughout; a further object being to provide a lever construction mounted in connection with the main body and cooperating with the supplemental body to control the vertical movement or adjustment of the supplemental body with reference to the main body, and further to provide a lock lever which cooperates with the first named levers to retain the supplemental body in predetermined positions of adjustment; a further object being to provide a beveled bearing face on the supplemental body or the separate members thereof which form the bearing face, whereby the plane may be used for cutting beveled as well as circular grooves or recesses in a workpiece; a still further object being to provide a vertical adjustable depth gage, the bearing face of which tapers forwardly and upwardly to a slight extent whereby the rear end thereof controls the depth of the cut, and said end is arranged adjacent the cutting edge of the tool; and with these and other objects in view, the invention consists in a plane of the class and for the purpose specified which is simple in construction, efficient in use, and which is constructed as herein-after described and claimed.

The invention is fully disclosed in the following specification, of which the accompanying drawing forms a part, in which the separate parts of my improvement are designated by suitable reference characters in each of the views, and in which:

Fig. 1 is a side view of the plane made according to my invention.

Fig. 2 is a plan view of the structure shown in Fig. 1, with part of the construction broken away.

Fig. 3 is a partial section on the line 3—3 of Fig. 2.

Fig. 4 is a section on the line 4—4 of Fig. 1.

Fig. 5 is a section on the line 5—5 of Fig. 3.

Fig. 6 is a partial section on the line 6—6 of Fig. 3.

Fig. 7 is a bottom, plan view of part of the plane.

Fig. 8 is a side view of the main stock of the plane, with all of the parts detached; and,

Figs. 9, 10 and 11 are sectioned, detail views of a workpiece, illustrating some of the different types of work which can be produced by my improved tool.

My improved plane consists of a main stock or body 12 and a supplemental stock or body 13. The lower or bearing faces of the main and supplemental stocks are in the form of narrow plates subdivided at spaced intervals to form a plurality of bearing members 12^a, 13^a, arranged in such manner that the members 12^a are adapted to mesh with, and arranged intermediate the members 13^a to form a continuous bearing face of the same thickness throughout as seen in Fig. 5 of the drawing. It is preferred that the bearing face of the supplemental stock 13 be beveled upwardly and outwardly as seen at 13^b, Fig. 6, in order to provide for beveled and circular cutting of the tool as later described.

Rigidly attached to the supplemental stock 13 adjacent the opposite end portions thereof are guide and gage rods 14, which extend through elongated apertures 15 in the main stock 12. These rods also pass through tubular bearings 16 carried by the free ends of arms 17, said arms being pivoted to the opposite end portions of the main stock as seen at 17^a. The upper faces of the rods 14 are provided with scale marks or graduations 14^a to aid in the adjustment of the supplemental stock 13. The upper faces of the tubular bearings 16 of the arms 17 are recessed at their outer ends as seen at 16^a to a depth equal to the width of the bearing faces of the stocks 12 and 13 in order to gage and

facilitate the proper adjustment of the tool. The supplemental stock is held in different positions of adjustment with reference to the main stock by set screws 18 carried by collars 18^a on the bearings 16 and which engage 5 the rods 14. Pivoted to the arms 17, inwardly of the pivots 17^a thereof as shown at 17^b are levers 19 and 20 which extend inwardly toward each other and are pivotally coupled together by a pivot pin or screw 21. The lever 20 is provided with an extension handle or member 20^a which extends beyond the pivot 21, and is provided with a finger piece 20^b by means of which both of said 15 levers may be operated. The lever 20 is also provided at opposite sides of the pivot with projecting bodies 22, extending in the direction of the lever 19 to provide a frictional engagement of said levers which is 20 adjusted by a wing nut 21^a on the pivot screw 21. The screw is carried by the lever 19 and operates in an elongated aperture 23 in the lever 20.

The handle portion 20^a of the lever 20 carries a pin 24 adapted to engage one of a number of recesses 25 in a lock lever 26 to support the levers 19 and 20 in predetermined position of adjustment. The lock lever 26 is pivoted to the stock 12 as seen 30 at 26^a and the pivoted end thereof engages a spring bar 27 to support the lever 26 normally in upright position to allow for a swinging movement into and out of engagement with the pin 24 at will. The forward 35 movement of the lever 26 is limited by a pin 26^b on the stock 12. Another lever 28 is pivoted to the stock 12 as seen at 28^a and its free end is adapted to cooperate with the pin 24 to retain the levers 19 and 20 40 against upward movement in any desired position of adjustment. Said lever 28 operates as a stop lever in this respect and is held in different positions of adjustment with relation to a pin 24 by a winged screw 45 29 in threaded engagement therewith and operating in an arc-shaped aperture 30 in the stock 12. The lever 28 is clamped to the stock by means of said screw. The free end portion of the lever 28 also carries a 50 pin 31 extending in the direction of the stock 12, which is adapted to cooperate with the upper edge of said stock as seen in Fig. 1 to gage the adjustment of the levers 19 and 20 in beveled or circular cutting of 55 the plane. In this adjustment, the lock lever 28 alone serves to control and limit the upward movement of the levers 19 and 20.

The levers 19 and 20 control the vertical 60 adjustment of the supplemental stock 13 with reference to the main stock 12 but the lateral adjustment or separation of said members is controlled by a winged adjustment screw 32 which passes through an elongated aperture 33 in the supplemental

70 stock 13 and is in threaded engagement with a bearing 34 on the stock 12. The screw 32 is coupled with and carried by the supplemental stock 13 by the collar construction 32^a as seen in Fig. 6 of the drawing. In the adjustment of the supplemental stock 75 toward and from the main stock, the double bearing 16 serves to support and guide the stock in its adjustment.

80 Mounted substantially at the central portion of the main stock 12 is a tool or cutter 35, the cutting edge 35^a of which is preferably arranged angularly with reference to the transverse plane of the tool to provide a better cutting edge. Said tool is held in position by the usual wedge or lock lever 85 36 pivotally supported in the stock 12 as seen at 37. Forwardly of the tool 35, the stock is provided with a vertical adjustable spur 38 which is held in different positions of adjustment by the head 39 of a screw, said head being beveled to correspond with the bevel of the stock 12 as seen at 40 in order to discharge the shavings laterally through one side of the tool in the operation thereof. A cylindrical nut 41 is mounted on the screw 39 to retain the spur 38 in its several positions of adjustment. The lower end of the spur is provided with 90 oppositely arranged spurs 38^a, the transverse dimensions of which correspond to the width of the tool 35 as well as bearing faces of the main and supplemental stocks 12 and 13.

95 Adjustably supported in a bearing 42 on the main stock 12 is a rod 43, the lower end of which carries an elongated shoe 44 which forms a depth gage controlling and regulating the depth of the cut in a workpiece. It is preferred that the bearing face of the 100 gage 44 be tapered forwardly and upwardly in order that the rear end of said gage which is arranged adjacent the spur and cutter be lower than the front end thereof, thus providing a free and easy action of 105 the tool and reducing friction. A screw 45 retains the depth gage 44 in different 110 positions of adjustment by its engagement with a clamp plate 46, which engages the rod 43.

115 The operation and use of my improved tool will be readily understood from the foregoing description when taken in connection with the accompanying drawing and the following statement. Assuming that 120 the main and supplemental stocks are in common alinement with the members 12^a—13^a in an interlocked relation as seen in Fig. 5 of the drawing, and it is desired to lower the supplemental frame into the position 125 shown in Fig. 3 of the drawing, the lever 26, if it should be in engagement with the pin 24 is moved forwardly out of engagement with said pin, and by pressing down 130 upon the finger piece 20^b the levers 19 and

20 are moved downwardly on their pivotal connection at 21. The arms 17 or the ends thereof carrying the cylindrical bearings 16 are also moved downwardly by the engagement of the levers 19 and 20 therewith until the desired depression or downward movement of the supplemental stock has been obtained. The lever 26 could then be moved into position to engage the pin 24 and retain said supplemental stock in its lower position. This might be regarded the normal position of the plane, as it is advisable to extend the supplemental stock below the surface of the main stock in order to guard and protect both the spur and the cutting edge 35^a of the tool. In order to cut a groove in a workpiece, and at a predetermined edge from the workpiece, for example the groove 47, Fig. 11 of the drawing, the supplemental stock 13 is adjusted to one side of the main stock to the required distance and the inner face of the supplemental stock is placed against the edge 48 of the workpiece in its downwardly extended position, and operates as a guide or straight edge to control and regulate the cutting of the groove 47. In the above described adjustment, the scale 14^a on the rods 14 guides the operator as will be understood. In a like manner, in cutting another groove 49 as seen in Fig. 11, the distance between said groove and the groove 47 previously formed, or the edge 48 of the workpiece may be regulated, or in cutting a wide groove as at 50 in said figure.

In the last event however, and when it is desirable to arrange the bearing faces of the main and supplemental stocks adjacent each other and gradually separate said bearing faces by the adjustment provided, and yet cut a groove of a common depth throughout its width as seen at 50, the lock lever 26 may be retained in its forward or inoperative position and out of engagement with the pin 24, and the stop lever 28 adjusted at a position which will limit the total vertical movement of the supplemental stock, but will leave said stock free to move vertically with reference to the main stock in gradually moving the main stock downwardly in producing a second cut. That is to say, assuming that the first cut of the groove 50 was of the width of the groove 49, the supplemental stock would then be placed in said groove when in an adjacent position to the main stock, and with said supplemental stock free to move forwardly, a groove twice the width of the groove 49 may be cut in the workpiece, and this operation continued to cut a groove of indefinite width, and at all times the groove would be of the same depth.

In this connection, it will also be understood that a groove half again as wide as the groove 49 may be cut by merely a slight

offsetting or a half offsetting of the bearing faces of the main and supplemental stocks, the only limitation of adjustment being the width of the bearing face of the main stock. It will be understood that a groove cannot be cut in one operation greater than the width of the cutting tool employed, but by virtue of the adjustability of the tool, grooves of any width may be cut.

It will also be understood that a step formation of grooves as indicated in Fig. 9 of the drawing may be arranged on the edge of a workpiece or within a workpiece, and the respective depths of the relative grooves may vary as indicated at 51 in said figure. In addition to the variation in the depth of the grooves, the width of the grooves may also vary. That is to say, they may be made wider or narrower in width as may be desired as indicated in said figure. By virtue of this possibility of workmanship, it will be understood that moldings of various kinds and classes in cross sectional form may be produced or reproduced for repair or other purposes.

If it be desired to provide beveled surfaces, the supplemental stock or body may be adjusted to a position controlled by the pin 31 on the stop 28. In this position, the beveled lower faces 13^b of the members 13^a extend to a slight extent below the flat bottom faces of the members 12^a providing a substantially beveled face to the plane. The tool, however, projects into said beveled face, and by holding the plane in an angular position governed by the beveled face 13^b such beveled cutting or grooving of a workpiece is possible; or if desired, and by reason of the comparatively fine cut in this adjustment, an arc-shaped surface such as seen at 52, Fig. 10 of the drawing may be produced in a workpiece. The arc is controlled only by the possible adjustment of the tool with regard to the slight extension of the beveled faces 13^b of the supplemental stock 13. In this cutting action, it is of course understood, that one corner portion of the cutting edge 35 only is in operation.

It is preferred that the threads of the adjustment screw be of the sixteen threads to the inch type. By virtue of this arrangement, it will be seen that at each complete revolution of this screw, which may be governed by the flat or winged head thereof, the supplemental stock 13 will be adjusted $\frac{1}{16}$ of an inch toward or away from the main stock 12, depending upon the direction of rotation. Likewise, a half revolution will provide $\frac{1}{32}$ of an inch movement, and a quarter of a revolution, $\frac{1}{64}$ of an inch movement, and as will be understood, two revolutions of the shaft will produce $\frac{1}{8}$ of an inch adjustment, etc. It is understood, however, that the scale 14^a on the rods 14 will provide for the accurate adjustment of

said parts, and the recesses 16^a serve to aid in adjusting the tool by placing the work-piece against the shoulder formed by said recess, and to take a measurement on the 5 scale 14^a in such manner as to compensate for the width of the bearing face of the plane, which is represented by the width or depth of the recesses 16^a.

It will be understood that while I have 10 shown certain details of construction for carrying my invention into effect, that I am not necessarily limited to these details, and various changes in and modifications of the 15 construction herein shown and described may be made within the scope of the appended claims, without departing from the spirit of my invention or sacrificing its advantages.

Having fully described my invention, 20 what I claim as new and desire to secure by Letters Patent, is:—

1. A plane of the class described comprising a main stock and a supplemental stock movable relatively to the main stock, means 25 involving pivotally coupled levers for moving the supplemental stock vertically with respect to the main stock and one of said levers extending beyond the coupling pivot to form a handle member permitting the operation of said levers, and a lock lever movable to engage and disengage the handle member of said lever and adapted to retain the supplemental stock in predetermined 30 position of adjustment.

2. A plane of the class described comprising a main stock and a supplemental stock movable relatively to the main stock, means involving pivotally coupled levers for moving the supplemental stock vertically with 35 respect to the main stock and one of said levers extending beyond the coupling pivot to form a handle member permitting the operation of said levers, a lock lever movable to engage and disengage the handle member 40 of said lever and adapted to retain the supplemental stock in predetermined position of adjustment, and a stop lever cooperating with said first named levers to limit the movement thereof in one direction.

3. A plane of the class described comprising a main stock and a supplemental stock movable relatively to the main stock, means involving pivotally coupled levers for moving the supplemental stock vertically with 45 respect to the main stock, said levers being pivotally supported by members movably supported with reference to the main stock, and rods on the supplemental stock adjustable transversely of said members and supported thereby, and said rods being movable with respect to the main stock.

4. A plane of the class described comprising a main stock and a supplemental stock movable relatively to the main stock, means 50 involving pivotally coupled levers for mov-

ing the supplemental stock vertically with respect to the main stock, said levers being pivotally supported by members movably supported with reference to the main stock, rods on the supplemental stock adjustable 70 transversely of said members and supported thereby, and said rods being movable with respect to the main stock, and means for retaining said levers and supplemental stock in different positions of adjustment. 75

5. A plane comprising a main stock, a supplemental stock having at its end portions guide rods extending at right angles to one side face thereof, said rods being passed freely through the main stock and 80 movable vertically therein to permit vertical adjustment of the supplemental stock, means movably supported on the end portions of the main stock for coupling said rods therewith, and means involving a manually operated member in operative connection with said last named means for raising and lowering said supplemental stock and the rods thereof. 85

6. A plane comprising a main stock, a supplemental stock having at its end portions guide rods extending at right angles to one side face thereof, said rods being passed freely through the main stock and 90 movable vertically therein to permit vertical adjustment of the supplemental stock, means movably supported on the end portions of the main stock for coupling said rods therewith, means involving a manually operated member in operative connection 95 with said last named means for raising and lowering said supplemental stock and the rods thereof, and means for limiting the movement of said last named means in one direction. 100

7. A plane comprising a main stock, a supplemental stock having at its end portions guide rods extending at right angles to one side face thereof, said rods being passed freely through the main stock and 110 movable vertically therein to permit vertical adjustment of the supplemental stock, means movably supported on the end portions of the main stock for coupling said rods therewith, means involving a manually operated member in operative connection 115 with said last named means for raising and lowering said supplemental stock and the rods thereof, and means for retaining said last named means in predetermined positions 120 of adjustment. 125

8. A plane of the class described comprising an elongated main stock having a comparatively narrow bearing face composed of spaced members, a supplemental stock mounted at one side of the main stock and having a bearing face of the same transverse dimensions as the bearing face of the main stock and composed of separate members adapted to intermesh with the mem- 130

bers of the main stock, the lower bearing face of the supplemental stock being beveled, and means for adjusting the supplemental stock with reference to the main stock.

9. A plane of the class described comprising an elongated main stock having a comparatively narrow bearing face composed of spaced members, a supplemental stock mounted at one side of the main stock and having a bearing face of the same transverse dimensions as the bearing face

of the main stock and composed of separate members adapted to intermesh with the members of the main stock, the lower bearing face of the supplemental stock being beveled, means for adjusting the supplemental stock with reference to the main stock, and means cooperating with said last named means for retaining the supplemental stock in predetermined positions of adjustment.

In testimony that I claim the foregoing as my invention I have signed my name.

WILLIAM POTTER.
